UNITED STATES PATENT OFFICE.

FRED G. DIETERICH AND JOHN U. O'MEARA, OF WASHINGTON, DISTRICT OF COLUMBIA; SAID DIETERICH ASSIGNOR TO SAID O'MEARA.

DESIGN FOR AN INDICATOR.

SPECIFICATION forming part of **Design No. 20,121**, dated **August 26, 1890**.

Application filed August 1, 1890. Serial No. 360,679. Term of patent 7 years.

To all whom it may concern:

Be it known that we, FRED G. DIETERICH and JOHN U. O'MEARA, residing at Washington, in the District of Columbia, have invented and produced a new and original Design for an Advertising or Indicator Top for Vending-Machines, of which the following is a specification, reference being had to the accompanying drawing, forming part thereof.

The leading feature of our design consists in a disk, the outlines of which in front elevation represent an annular paneled portion *a*, which is surrounded by a series of radial-like spaces *b*, about which a second row of spaces *c* is formed. The circumferential edge is scalloped, as at *d*, and formed at in-

tervals with radial-like projections *e*. Below the disk a representation of an ornamental standard-like frame is produced, while above the same a suitable ornament, like the horse *f*, is shown, the whole giving the appearance of a disk mounted upon an ornamental standard.

What we claim is—

The design herein shown and described. 25
In testimony whereof we affix our signatures in presence of two witnesses.

FRED G. DIETERICH.
JNO. U. O'MEARA.
